UNITED STATES PATENT OFFICE

2,479,117

ROTARY CYLINDER COMPRESSOR

Carl Gunnar Jarne, Finspong, Sweden

Application September 29, 1947, Serial No. 776,654
In Sweden October 4, 1946

5 Claims. (Cl. 230—140)

1

The present invention relates to rotary compressors of the type comprising a rotatable cylinder having a female thread and a screw-threaded piston eccentrically mounted in said cylinder so as to form a continuous crescent-shaped working chamber between its own screw-thread and the female thread of the cylinder. Preferably, the piston rotates at the same or substantially same angular velocity as the cylinder.

The invention is characterized, chiefly, by the fact that the threads of the cylinder and piston comprise one sided square threads tapering conically and, as viewed in an axial section, step-like from the suction side to the pressure side of the machine.

In the accompanying drawing Fig. 1 is an axial section of an embodiment of the invention, Fig. 2 is an axial section of another embodiment, and Figs. 3-5 are detail views.

With reference to Fig. 1 the numeral 1 designates the cylinder and 2 is a motor shaft formed integrally with or rigidly connected to the cylinder 1. Formed on the external surface of the cylinder are cooling ribs 3. The inside surface of the cylinder is shaped as a female thread 4, tapering conically and, as viewed in an axial section, step-like from the suction side of the cylinder, as represented by an intake port 5 formed in a cover 6 at one end of the cylinder, towards the pressure side as represented by a pressure chamber 7 adjacent the other end of the cylinder. Located in the cylinder 1 is a piston 8 the thread of which is similar in shape to that of the cylinder. The piston is mounted eccentrically with relation to the cylinder 1 by means of a journal 9 engaging a bushing 10 which is attached to a stationary casing 11 by means of a screw 12. As shown, the said two coengaging threads are in contact with each other only at their uppermost points thereby giving rise to a set of crescent-shaped working chambers between the cylinder and the piston. When the cylinder 1 rotates the screw-threaded piston is also caused to rotate. In this rotation the crescent working chambers which are closed at their uppermost points, as already stated, will move towards the pressure chamber 7 while being subjected to a continuous reduction of their volumes, thereby effecting a corresponding compression of the medium contained therein. The compressed medium is discharged from the pressure chamber 7 through a channel 13 extending through the journal 9 and a channel 14 formed in the stationary casing 11.

The embodiment shown in Fig. 2 differs from that above described substantially by the feature

2

that the screw-threaded piston 8 is hollow and on its inside provided with a female thread 15 of the same shape as its screw-thread. Said female thread 15 is engaged by a screw-thread 16 formed on an inner member 17 rigidly connected to the cylinder 1. By this means working chambers are obtained both outside and inside the threaded piston 8 with a resulting redoubling of the capacity of the compressor. The working medium enters through port 5 and is discharged after compression through the channels 13 and 14. In order to obtain a tight sealing between the threads packing strips 18 and 19 are placed in grooves formed in the respective members. Such strips may be of the shape shown in Fig. 3. To manufacture such a strip a spiral slot is cut in a sheet metal plate. The inner end of the spiral strip thus obtained may be provided with a bushing 20 to receive a helical spring 21 the object of which is to force the tightening strip against the respective tightening surface. In Fig. 4 is shown a section on the line 22 of Fig. 3 taken on a somewhat larger scale.

Fig. 5 is an axial section of a portion of an externally and internally threaded piston comprising two resilient members 23 and 24 engaging each other to secure a tight sealing. Each of said members comprises an angle bar bent to a spiral shape in hot state.

30 By introducing a gas in the opposite direction to that of the medium above supposed and allowing it to expand in the machine a motor will be obtained.

What I claim is:

1. In a machine of the class specified the combination of a first rotatable member having a cavity bounded by radial and peripheral helical surfaces in echelon formation and of diameters gradually reduced towards the inner end of the cavity so as to form a one-sided square helical female thread of correspondingly reduced diameter, a second rotatable member eccentrically mounted in said first-mentioned member, said second member having a similar one-sided square helical screw thread on its peripheral surface for engaging the female thread of said first member, the dimensions of said threads being so proportioned as to give rise to the formation of a set of crescent-shaped fluid receiving working chambers of gradually varying capacity, and means for effecting a tight sealing between co-engaging surfaces of said threads.
2. In a machine of the class specified the combination of a first rotatable member having a cavity bounded by radial and peripheral helical

surfaces in echelon formation and of diameters gradually reduced towards the inner end of the cavity so as to form a one-sided square helical female thread of correspondingly reduced diameter, a second hollow rotatable member eccentrically mounted in said first-mentioned member, said second member having one-sided square threads formed by radial and axial helical surfaces of gradually varying diameters both on its external and internal surfaces, said external thread being arranged to engage the female thread of the said first member for providing therein a set of crescent-shaped working chambers of gradually decreased capacity, a third rotatable member rigidly connected with said first rotatable member, said member having a one-sided square helical screw thread of gradually varying diameter for engaging the internal thread of said second member, and packing strips inserted between the threads of the second member and those of the first and third members.

3. In a machine of the class specified the combination of a first rotatable member having a cavity bounded by radial and peripheral helical surfaces in echelon formation and of diameters gradually reduced towards the inner end of the cavity so as to form a one-sided square helical female thread of correspondingly reduced diameter, a second rotatable member eccentrically mounted in said first-mentioned member, said second member having a similar one-sided square helical screw thread on its peripheral surface for engaging the female thread of said first member, the dimensions of said threads being so

proportioned as to give rise to the formation of a set of crescent-shaped fluid receiving working chambers of gradually varying capacity, and flexible packing strips provided between coengaging radial surfaces of the threads for effecting a tight sealing between the coengaging threads.

5. In a rotary machine as claimed in claim 1, and in which the second member is hollow and provided with an external screw-thread and an internal female thread, the further feature that the second member comprises two resilient members.

15 6. In a rotary machine as claimed in claim 1, and in which the second member is hollow and provided with an external screw-thread and an internal female thread, the further feature that the second member comprises two helically bent angle bars one of which surrounds the other.
